CLAIM

The ornamental design for a container cap, as shown and described.

DESCRIPTION

FIG. 1 is a perspective view of a container cap showing my new design;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a first partially exploded perspective view of the design of FIG. 1;

FIG. 7 is a second partially exploded perspective view of the design of FIG. 1;

FIG. 8 is a partially exploded first side view of the design of FIG. 1; and,

FIG. 9 is a partially exploded second side view of the design of FIG. 1.

The broken lines depict portions of the container cap that form no part of the claimed design.

The wavy lines in FIGS. 1 and 5–7 represent surface shading.
